UNITED STATES PATENT OFFICE.

CHARLES F. McBEE, OF ATHENS, OHIO, ASSIGNOR TO THE McBEE BINDER CO., A CORPORATION OF OHIO.

BACK FOR LOOSE-LEAF FILES.

1,405,602.

Specification of Letters Patent. Patented Feb. 7, 1922.

Application filed September 18, 1919. Serial No. 324,297.

To all whom it may concern:

Be it known that I, CHARLES F. McBEE, a citizen of the United States, residing at Athens, in the county of Athens and State 5 of Ohio, have invented certain new and useful Improvements in Backs for Loose-Leaf Files, of which the following is a specification.

This invention relates to loose leaf files 10 of the class described in my application for patent for loose leaf binders, filed Sept. 6, 1919, Serial No. 322,005, and has for its object to provide backs for such files and means to retain the backs in position so that 15 it will not interfere with removing or adding sheets to the file at any desired time.

My invention consists of the details of construction hereinafter set forth, pointed out in my claims and illustrated in the accompanying drawing, in which—

Fig. 1 shows a perspective view of a compiled loose leaf volume fitted out with my device.

Fig. 2 shows a perspective view of the 25 lower cover and sheets of a loose leaf volume with my improved back ready to be fitted thereon, the dotted line showing the back in position.

Fig. 3 shows a transverse sectional view 30 taken on the line 3—3 in Fig. 1.

Fig. 4 shows a detail view in section taken on line 4—4 in Fig. 1, a part of same being broken away.

Referring to the accompanying drawing, 35 the reference numerals 10 and 11 indicate the upper and lower covers respectively of the loose leaf volume to be formed, the lower cover thereof being perforated to register with the perforations in the sheets to be 40 filed. A plate 12, also perforated to register with the perforations in the sheets to be filed, is designed to underlie the said sheets and be positioned between the upper surface of the lower cover and the lowermost 45 sheet of the file. A strip of canvas, or similar substance, designed to form a back for my volume on which identification marks may be placed, underlies the plate 12 and extends outwardly therefrom, its inner end 50 extending inwardly a sufficient distance so that it may be doubled back over the upper surface of the plate and the end extending beyond the rear edge of the sheets to be filed, as shown in Fig. 2. A plate 14 also perforated to register with the perforations in the sheets to be filed, is designed to rest upon the top of the uppermost sheet in the file, and the canvas back is designed to engage both the upper and lower surface of the said plate and be doubled thereon, as shown in 60 Fig. 2, prior to the time that the upper plate is placed in position on the uppermost sheet.

The plate 14 is being placed in position, a U-shaped wire, or metal strip 15, or the like, is threaded upwardly through perforations in the lower cover, the lower plate, the sheets to be filed, and the upper plate, its two ends being turned inwardly towards each other after the sheets have been pressed 70 down into position. It is obvious this will hold the lower cover, the two plates, and the sheets, and also the back 13 in proper position with each other.

The plate 14 is provided with a plurality 75 of screw threaded lugs 16 extending upwardly and designed to register with perforations in the upper cover into which they project, and headed screw caps 17 extending downwardly through the perforations in the 80 upper cover, engage the said lugs so as to hold the upper cover firmly in position.

The back 13 may, obviously, be adjusted to fit any size volume desired.

Having thus described my invention, 85 what I claim and desire to secure by Letters Patent of the United States, is:

1. A loose leaf file comprising a lower cover orificed to register with orifices in the sheets to be bound, a plate to be positioned 90 between the lower cover and the sheets, and a plate to be positioned above the sheets, each of said plates orificed to register with the orifices in the lower cover and sheets, a flexible back of indeterminate length designed to be fitted to the desired volume and held in permanent position by being doubled back over the said plates, a binding means to pass through the lower cover sheets and plates and hold them and also the flexible back in position, substantially as shown and described.

2. A loose leaf file comprising a lower cover orifice to register with orifices in the sheets to be bound, a plate to be positioned 105 between the lower cover and the sheets, and a plate to be positioned above the sheets, each of said plate orifice to register with

the orifices in the lower cover and sheets, a flexible back of indetermined length designed to be fitted to the desired volume and held in permanent position by being doubled back over the said plates, a binding means to pass through the lower cover sheets and plates and hold them and also the flexi-

ble back in position, and an upper cover and means to secure same to the upper plate, substantially as shown and described. 10

In testimony whereof I have signed the foregoing specification.

CHARLES F. McBEE.
